UNITED STATES PATENT OFFICE.

WILLIAM LEONARD HERBLIN, OF GAINESVILLE, TEXAS.

CAN-SPOUT.

1,056,790.

Specification of Letters Patent. Patented Mar. 25, 1913.

Application filed March 6, 1912. Serial No. 682,055.

To all whom it may concern:

Be it known that I, WILLIAM LEONARD HERBLIN, a citizen of the United States, residing at Gainesville, in the county of Cooke and State of Texas, have invented certain new and useful Improvements in Can-Spouts, of which the following is a specification, reference being had to the accompanying drawings.

10 This invention relates to new and useful improvements in stoppers and discharge spouts for cans, or receptacles more particularly to cans employed in shipping kerosene oil, cotton seed oil, turpentine syrups and 15 various other liquids.

The object of the invention is to provide a stopper adapted for insertion into and removal from the can, said stopper having its outer end flush with the outer surface of 20 the can when inserted therein.

Another object of the invention is to provide a discharge spout to be used in connection with the stopper and adapted to be stored or concealed when not in use within 25 the can or other vessel and to project therefrom when in use.

A further object of the invention is to provide a device of this character which will possess advantages in points of efficiency and durability, is inexpensive of 30 manufacture and at the same time is simple in construction and operation.

With the above and other objects in view the invention consists in the novel features 35 of construction the combination and arrangement of parts hereinafter more fully described, pointed out in the claim and shown in the accompanying drawings, in which—

40 Figure 1 is a sectional view of a portion of a can showing my improved spout concealed within the can. Fig. 2 is a similar view showing the spout projected ready for use and Fig. 3 is a sectional view on the 45 line 6—6 of Fig. 1.

Referring more particularly to the drawings, 1 indicates the body of a can which may be made in any suitable shape and provided with an internally-tapped nipple 2 50 extending into the can or other vessel, in order that the nipple 2 may be beneath the general plane of the can to permit of a number being tacked upon one another for

shipment without denting, bending or otherwise injuring the same.

55

An angular spout 12 is provided having an externally threaded plug 13 secured to the base portion thereof and adapted to be threaded into the nipple 2. One end of the plug 13 is cut away upon opposite sides 60 as shown at 14 to form the vertically disposed grasping portions 15 so that when the spout 12 is arranged within the can in an inverted position, the portion 15 can be easily grasped by the fingers to unscrew the 65 plug. The plug 13 is rounded off at both ends as shown at 16 to fit snugly down upon the closed end of the nipple. When the spout 12 is arranged in the can in an inverted position, a stopper 17 is threaded in 70 the large end thereof to prevent leakage. While I have shown in the drawings a headed plug threaded into the large end of the spout when the same is disposed in an inverted position, it will be understood that a 75 cork or other form of stopper may be used, if desired.

From the foregoing description taken in connection with the drawings it will be seen that I have provided a simple, durable 80 and efficient discharge spout, which, when not in use will be stored or concealed in a can or vessel so as to permit of a number of cans being packed upon one another for 85 shipment without denting, bending, or otherwise injuring the same.

While I have shown and described the preferred form of my invention it will be obvious that various changes in the details of construction and in the proportions may 90 be resorted to for successfully carrying my invention into practice without sacrificing any of the novel features or departing from the scope thereof.

Having thus described my invention, what 95 I claim is—

In a device of the character described, the combination of an internally-tapped nipple integral with one of the walls of the receptacle, an angular spout having a plug 100 formed on its base portion and adapted to be threaded into said nipple, said spout being adapted to be concealed within the receptacle when not in use or projected therefrom when in use, one end of said plug being 105 cut away to form vertically disposed

grasping portions arranged at diametrically opposite points so that when the spout is disposed in an inverted position, the plug can be easily unscrewed, and a stopper 5 threaded into the large end of the spout when the same is disposed in an inverted position.

In testimony whereof I hereunto affix my signature in the presence of two witnesses.

WILLIAM LEONARD HERBLIN.
